US00D791306S

(12) **United States Design Patent** (10) **Patent No.:** **US D791,306 S**
(45) **Date of Patent:** **** Jul. 4, 2017**

(54) **DRUG DELIVERY PUMP**

- (71) Applicant: **UNITRACT SYRINGE PTY LTD**,
Sydney (AU)
- (72) Inventors: **Matthew J. Clemente**, Downingtown,
PA (US); **Ian B. Hanson**, Wayne, PA
(US); **Paul F. Bente, IV**, Wayne, PA
(US); **Ryan M. Agard**, Royersford, PA
(US); **Nicholas J. Ciccarelli**,
Philadelphia, PA (US); **Kun-Chi Wu**,
Princeton, NJ (US)
- (73) Assignee: **Unitract Syringe PTY LTD**, Sydney
(AU)

(**) Term: **14 Years**

(21) Appl. No.: **29/479,414**

(22) Filed: **Jan. 15, 2014**

CLAIM

The ornamental design for a drug delivery pump, as shown and described.

DESCRIPTION

FIG. 1 is a top, left side isometric view of a drug delivery pump;

FIG. 2 is a bottom, left side isometric view thereof;

FIG. 3 is a top, left side isometric view thereof;

FIG. 4 is an end elevation view thereof;

FIG. 5 is the opposite end elevation view thereof;

FIG. 6 is a right side elevation view thereof;

FIG. 7 is a left side elevation view thereof;

FIG. 8 is a bottom plan view thereof; and,

FIG. 9 is a top plan view thereof.

The broken line showing portions of the article is included for the purpose of illustrating unclaimed subject matter with the line itself and the unshaded surfaces within forming no part of the claimed design.

1 Claim, 5 Drawing Sheets
